GOLF PUTTER

Karsten Solheim, 10412 N. 37th St., Phoenix, Ariz.

Filed Jan. 4, 1965, Ser. No. 83,264

Term of patent 14 years

(Cl. D34—5)

FIG. 1 is a front view in perspective of a golf putter embodying my new design;

FIG. 2 is a rear fragmentary view in perspective of the same; and

FIG. 3 is a sectional view taken on the line 3—3 of FIG. 2.

I claim:

The ornamental design for a golf putter, substantially as shown.
